ABSTRACT

First and second carding units are provided. Each carding unit comprises a smooth feeder conveyor belt, a smooth covering conveyor belt extending over and parallel to said feeder conveyor belt to define a space therewith and moving in the same direction as the feeder conveyor belt, a carding drum for disintegrating fibrous material and for ejecting disintegrated fibrous material, and a pair of feed rollers for receiving fibrous material from said space between said feeder and covering conveyor belts and for feeding said fibrous material to said carding drum. The apparatus further comprises charging means preceding said covering conveyor belt of said first carding unit and adapted to charge fibrous material into said space between said feeder and covering conveyor belts of said first carding unit, and drive means for driving said feed rollers and for driving said feeder and covering conveyor belts of each of said carding units at a surface velocity which is higher than the surface velocity of the feed rollers of the same carding unit. The carding drum of said first carding drum is operable to eject disintegrated fibrous material onto said feeder conveyor belt of said second carding unit.

4 Claims, 1 Drawing Figure

APPARATUS FOR DISINTEGRATING FIBROUS MATERIAL AND FOR DELIVERING DISINTEGRATED FIBROUS MATERIAL

This invention relates to apparatus for feeding lap machines or the like, comprising a carding unit, which consists of a feeder belt conveyor, a pair of feed rollers, and a carding drum.

In a known apparatus of that kind the carding drum is succeeded by a weighing device, which ensures that the material is delivered to the lap machine at a constant weight rate. The feeder belt conveyor is charged by hand. Whereas this operation does not require special care, the intervals of time between successive charging operations must be relatively short because the length of the feeder belt conveyor is limited for structural reasons and the function of that belt conveyor will be adversely affected if the layer of material on said conveyor exceeds an upper limit. For these reasons, the quantity of material which can be charged to the feeder belt conveyor at one time is limited.

Other feeders, so-called fox feeders, have been disclosed, which consist of a material storage bin and a conveyor for continuously taking and delivering material at a low rate. In these systems the bottom of the storage bin consists of a conveyor belt, which moves the material to the upwardly inclined conveyor. Because the storage bin has a high capacity, the box feeders need not be charged only after much longer intervals of time. On the other hand they have the disadvantage that they do not enable a uniform taking and delivery of the material because the conveyor consists in most cases of an upwardly inclined lattice apron, which is set with spikes, or a similar element which is not sufficiently adaptable to the mass of material in the storage bin and for this reason takes and delivers material in different quantities in different areas of the conveyor element.

An improvement has been afforded by another known feeding apparatus in which the material is taken from the storage bin by a conveyor which consists of a multiplicity of conveyor arms, which revolve in parallel planes and are set with teeth at their ends and through a grata-like, slotted wall extend into the storage bin. That feeding apparatus too is not entirely satisfactory. This is due to the fact that a circulation is imparted to the material in the storage bin by the revolving conveyor belt which forms the bottom of the storage bin and by the boundary wall which is slotted like a grate. This circulation is due to the fact that the conveyor which forms the bottom of the storage bin continually moves the material to the grata-like wall, where the material is discharged only at a low rate, whereas the remaining material rises and falls back. This continuous circulation in the storage bin causes the material to bunch whereby the continuous taking of the material at a uniform rate is adversely affected. As a result, the specific gravity and the bulk of the material taken from the storage bin by the conveyor vary continuously. This fact results in undesired irregularities in the web which is subsequently formed.

It is an object of the invention to avoid these disadvantages and provide an apparatus which is of the kind described first hereinbefore and which can be charged with material in any desired quantities and in any desired intervals of time and yet ensures a delivery of the material at a constant rate and with a constant specific

gravity and bulk. The apparatus should be comparatively simple and reliable in operation.

This object is accomplished according to the invention in that a covering conveyor belt is provided, which is disposed over the feeder conveyor and moves in the same direction as the latter, in known manner, that the feeder conveyor belt and the covering conveyor belt have smooth, spacedly opposite faces which extend parallel to one another, that their surface velocity is a plurality of the surface velocity of the feed rollers, that the carding drum is succeeded by a second, identical carding unit, which comprises a feeder conveyor belt receiving the material ejected from the first carding drum and a covering conveyor belt disposed over the feeder conveyor belt of the second carding unit, and that the surface velocity of the feed rollers of the second unit is also much smaller than the surface velocity of the smooth conveyor belts which feed said feed rollers. The first carding unit has a storage bin associated therewith and the material can be charged into said storage bin through a filling chute in any desired quantities and in any desired intervals of time by hand or by a bale opener or the like. Because the two belt conveyors between which the supply of material is disposed have a higher surface velocity than the feed rollers, the material is retained before said rollers so that a continuous taking of the material is enabled even when the material is intermittently supplied. The two conveyor belts are smooth and for this reason can slip under or over the material retained before the pair of feed rollers and do not cause the material to be compressed. The material is not circulated before the pair of feed rollers associated with the carding drum because such circulation is prevented by the sense of rotation of the feed rollers and because the two conveyor belts tend to move the material toward the feed rollers. Because the two revolving conveyor belts are parallel to each other, the conditions of the material before the feed rollers are always the same so that the material is entrained by the feed rollers, disintegrated into individual fibers by the first carding drum and ejected by the latter onto the feeder conveyor belt of the second carding unit at a constant rate. In the second carding drum, the same operations are performed so that the uniformity is increased further, as desired. This eliminates the need for a succeeding weighing device or the like because the two carding drums together ensure that the material is delivered from the second carding drum to the lap machine at an exactly uniform rate.

Whereas it is already known to provide before a card or the like two conveyor belts which are arranged one over the other and which act in the same direction and are provided with a filling chute, the known arrangements do not provide for a rate control but serve only for feeding the material to the inlet of the card or the like. For this reason the surface velocity of the conveyor belts corresponds to the surface velocity of the feed rollers or feed roller and the two conveyor belts do not extend parallel to each other but define a space which tapers toward the entrance to the carding drum or the like.

To avoid a feeding of material to the second carding unit at a rate which is higher than the rate at which said second carding unit can deliver material to the lap machine, photo-electric sensing unit is provided, which is disposed adjacent to the entrance to the space between the conveyor belts of the second carding unit and

whose light beam extends transversely to the direction of travel of the material and deenergizes the means for driving the first carding unit, particularly the pair of feed rollers thereof, when the beam is interrupted by the material which has built up on the feeder conveyor belt of the second unit. When too much material has built up on the feeder conveyor belt of the second unit, the delivery of material by the first unit is interrupted in that its feed rollers are stopped. When the material has been conveyed further on the feeder conveyor belt 10 of the second unit and the light beam is free again, the pair of feed rollers of the first unit are started again. This arrangement results in a simple but effective control of the entire feeding apparatus.

An embodiment of the feeding device according to 15 the invention is shown by way of example on the accompanying drawing in sectional side elevation.

The feeding apparatus according to the invention is composed of two carding units I, II. The first carding unit I comprises a feeder conveyor belt 1, a pair of feed 20 rollers 2 and a carding drum 3. The feeder conveyor belt 1 is particularly smooth. Another smooth covering conveyor belt 4 extends over and parallel to the feeder conveyor belt and moves in the same direction as the feeder conveyor belt from a material receiving area to 25 a material discharging area. The covering conveyor belt 4 is preceded by a filling chute 5, which opens into the space between the conveyor belts. The surface velocity imparted to the two conveyor belts 1, 4 by respective pulleys 11, 12 is a multiple of the surface velocity imparted to the feed rollers 2 by their shafts 13, 14. The carding drum 3 disintegrates the material into 30 individual fibers and ejects the same onto the feeder conveyor belt 1' of the second carding unit II. A covering conveyor belt 4' extends over and parallel to the feeder conveyor belt 1' and moves in the same direction as the feeder conveyor belt 1'. The two conveyor belts 1', 4' are succeeded by a pair of feed rollers 2' and these are succeeded by a carding drum 3', which by means of an ejecting chute 6 delivers the disintegrated material to the lap machine or the like. The two conveyor belts 1', 4' are also smooth, and the surface velocity imparted to them by pulleys 15, 16 respectively is much higher than the surface velocity of the pair of feed rollers 2' rotated by drive shafts 17, 18. 45

A photo-electric sensing unit 7 is disposed adjacent to the entrance to the space between the conveyor belts of the second carding unit II. The apparatus 19 for driving the pair of feed rollers 2 of the first carding unit I

50

is deenergized whenever the light beam of the unit 7 is interrupted by the material which has built up on the feeder conveyor belt 1'.

What is claimed is:

1. Apparatus for disintegrating fibrous material comprising:
  - a. a first carding unit;
  - b. a second carding unit, each carding unit including
    1. two elongated conveyor belts having respective smooth, longitudinal faces spacedly opposite each other in parallel relationship,
    2. first drive means for driving said belts at a predetermined common velocity of said faces in the same direction from a material receiving to a material discharging area,
    3. a pair of feed rollers arranged in said material discharge area for receiving material discharged from by said belts,
    4. a carding drum arranged adjacent said feed rollers,
    5. second drive means for driving said feed rollers at a surface velocity smaller than said common velocity of said faces and for thereby transferring material discharged by said belts to said carding drum; and
  - c. charging means for charging the material to be disintegrated to said conveyor belts of said first carding unit,
1. the carding drum of said first carding unit being arranged for discharging material received from the feed rollers of said first carding unit to the belts of said second carding unit.
2. Apparatus as set forth in claim 1, further comprising discharge means for discharging disintegrated fibrous material from the carding drum of said second unit.
3. Apparatus as set forth in claim 1, wherein said charging means include a chute open toward one of the conveyor belts of said first carding unit.
4. Apparatus as set forth in claim 1, further comprising sensing means for sensing the amount of fibrous material between said faces of the conveyor belts in said second carding unit adjacent the material receiving area, said sensing means being operatively connected to the second drive means of said first carding unit for stopping the feed rollers of said first carding unit in response to a sensed predetermined amount of fibrous material.
